Primary Examiner — Richard E Chilcot(74) *Attorney, Agent, or Firm* — LEGALFORCE RAPC WORLDWIDE(57) **CLAIM**

The ornamental design for a simulated bamboo LED torch light, as shown and described.

DESCRIPTION

FIG. 1 is a front top left side perspective view for a simulated bamboo LED torch light, showing my new design;

FIG. 2 is a front elevational view of FIG. 1 thereof;

FIG. 3 is a rear elevational view of FIG. 1 thereof;

FIG. 4 is a left side elevational view of FIG. 1 thereof;

FIG. 5 is a right side elevational view of FIG. 1 thereof;

FIG. 6 is a top plan view of FIG. 1 thereof; and,

FIG. 7 is a bottom plan view of FIG. 1 thereof.

In FIGS. 1-5, the post is shown with a break line in its length that forms no part of the claimed design. The appearance of any portion of the article between the break lines forms no part of the claimed design.

The broken lines indicate unclaimed portions of the simulated bamboo LED torch light and form no part of the claimed design.
